FLOATING TYPE MANDREL FOR TUBE
DRAWINGCarl H. Wadell, Fairfield, Conn., assignor to
Bridgeport Brass Company, Bridgeport, Conn.,
a corporation of Connecticut

Application March 17, 1943, Serial No. 479,425

11 Claims.

(Cl. 205—7)

This invention relates to improvements in tube drawing apparatus, and more particularly to a floating plug construction for use in connection with conventional draw-bench constructions and drawing dies.

An object of this invention is to provide a construction of this character which will be compensating or self accommodating to imperfections on the inside surface of the tube being drawn, and to variations of tube wall thickness thereof.

Another object of this invention is to provide a plug construction that will be less subject to breakage or damage as a result of such imperfections or variations.

A further object of this invention is to provide such construction as will result in great economies in use and in which damage to the sizing mandrel or sleeve will not necessarily require replacement of said sleeve or of the entire tool.

Still another object of the invention is to provide a construction in which the same mandrel shank may be utilized for differently sized sizing mandrels or sleeves, resulting thereby in eliminating the cost of more than one mandrel shank for several sizes of sizing mandrels or sleeves.

To the accomplishment of the foregoing and such other objects as may hereinafter appear, this invention consists in the novel construction and arrangement of parts hereinafter described and then sought to be defined in the appended claims, reference being had to the accompanying drawings forming a part hereof, which show merely for the purposes of illustrative disclosure a preferred embodiment of the invention, it being expressly understood, however, that various changes may be made in practice within the scope of the claims without digressing from the inventive idea.

In the drawings in which similar reference characters denote corresponding parts:

Fig. 1 is a side elevation partially in section of a draw bench, die and floating plug construction in accordance with the present invention;

Fig. 2 is a perspective view of the separated parts of the floating plug construction;

Fig. 3 is a longitudinal section of an assembled floating plug construction;

Fig. 4 is a section taken along line 4—4 of Fig. 3 viewed in the direction of the arrows;

Fig. 5 is a section taken along line 5—5 of Fig. 3 also viewed in the direction of the arrows;

Fig. 6 is an end view seen in the direction of the arrow 6 of Fig. 3; and

Fig. 7 is a fragmentary longitudinal section

showing relative displacement of the sizing mandrel on its retaining stud.

Referring to the drawings, a draw bench construction 10 including a trough 11 and having a drive chain 12 for moving the draw carriage 13 all of usual construction may be employed. A die 14 is mounted on the draw bench, and tube 15 is adapted to be drawn therethrough by means of the carriage 13 in well known manner.

10 A floating plug or mandrel 16 is placed within the die and the tube. This plug or mandrel 16 consists of a mandrel shank 17 which is provided with a portion 18 of enlarged diameter at one end. The shank is provided at this end with an axially extending bore 19 which is countersunk at 20, and provided internally with a tapped or threaded portion 21, and a portion 22 of reduced diameter.

20 A retaining stud 23 is formed with a threaded portion 24 adapted to threadedly engage the threaded portion 21 of the shank. This stud also has a reduced end portion 25 adapted to fit within the portion 22 of the bore of the shank and a portion 26 adapted to fit within the countersunk portion 20 and to extend outwardly of the shank. A head 27 is provided on the end of the outwardly extending portion 26. This head has an abutment flange 28 and a rounded portion 29 of reduced diameter which may be provided with flattened sides 30 to permit application of a tightening tool or the like. The overall outside diameter of the flange 28 is less than the maximum outside diameter of the shank 17.

The retaining stud 23 carries a loosely fitting 35 sizing mandrel or sleeve 32. This sleeve mandrel is substantially shorter than the stud, i. e. the distance between the end 18a of the shank 17 and the flange 28. The internal diameter of the sleeve mandrel is greater than the diameter of the portion 26 of the stud 23 so that said sleeve mandrel may be shifted or moved laterally of as well as longitudinally with respect to the stud axis. The wall 32a of the sleeve may be tapered if desired. The leading edge 33 of the sleeve is tapered preferably with approximately a 45° taper while its trailing edge 34 is rounded to eliminate any cutting edges on said sleeve mandrel. A suitable coil spring 35 is carried on the stud 23 and serves to urge the sleeve into abutment with the flange 28. The flange 28 has a lesser diameter than the outside diameter of the sleeve 32 and preferably a lesser diameter than that of the leading end 32b of said sleeve.

40 The other end of the shank 17 is provided with a tapped bore 37 in which a rod 38 threadedly en-

gages. The opposite end of the rod is suitably guided and held in a tail stock 39 in well known manner during the drawing operation.

During the draw, imperfections on the inside surfaces of the tube, and the lack of uniformity of the tube thickness are compensated for by the lateral displaceability of the mandrel sleeve 32 with respect to the stud 23. Thus in Fig. 7, the said sleeve 32 is shown displaced from concentricity with respect to the axis of stud 23 to substantially the limit permitted by the difference in the diameter of the stud and the internal diameter of the sleeve a condition resulting from abnormally thick tubing wall on one side of the sleeve. Normally the sleeve 32 is self centering, being positioned as shown in Fig. 3 when uniform wall thickness is encountered during the draw. The displaceability of the sleeve is of great importance as it eliminates breakage that would occur with a rigidly positioned mandrel, encountering tube conditions tending to produce the position of the sleeve shown in Fig. 7.

Another great advantage of the novel construction is that the same shank and stud can be utilized to mount replaceably several different sizes of mandrel sleeves 32.

For example, with a stud diameter in the portion 26 of .437 inch mandrel sleeves each having an inside diameter large enough to permit floating action and respectively any outside diameter that allows sufficient shell wall strength. Other sizes, too, are contemplated.

Another important advantage is that the mandrel construction described results in great economy. This is so because mandrel sleeves can be replaced on the same mandrel shank without any machining or fitting thereby making it unnecessary to provide separate mandrel shanks for each mandrel sleeve. The savings are in the order of twenty dollars per shank.

Economy also results from the fact that damage to the mandrel sleeve 32 adjacent either of its ends does not require that the sleeve be discarded. It may be trimmed off to eliminate the damaged portions. In such event, the spring 35, of course, must be replaced by a longer spring to compensate for the shortened sleeve length. Since these sleeve mandrels are very expensive, the savings are material and apparent.

In the embodiment described, the stud 23 is preferably of heat-treated tool steel, the shank can be of any commercial tool steel that may be heat treated, while the sleeve mandrel is of cemented tungsten carbide, one commercially available material therefor being "Carboloy."

While specific constructional details have been described, and specific dimensional characteristics mentioned as well as specific materials, it is to be understood that variations in structure, dimensions and materials are contemplated within the scope of the claims. There is no intention of limitation to the exact details described.

What is claimed is:

1. A tube drawing mandrel construction comprising a mandrel shank, a retaining stud extending from said shank and a sizing mandrel or sleeve carried on said stud and being displaceable longitudinally and a material amount laterally with respect to the axis thereof.

2. A tube drawing mandrel construction comprising a mandrel shank, a stud carried by said shank, a sizing mandrel or sleeve removably carried on said stud, said mandrel or sleeve having a substantially larger internal diameter than the

external diameter of said stud to permit material lateral displacement of said sleeve on said stud, retaining means in conjunction with said stud, and means carried on said stud for urging said mandrel or sleeve into abutment with said retaining means.

3. A tube drawing mandrel construction comprising a mandrel shank, a stud carried by said shank, a sizing mandrel or sleeve removably carried on said stud, said mandrel or sleeve having a substantially larger internal diameter than the external diameter of said stud whereby said mandrel or sleeve may be displaced longitudinally and a material amount laterally on said stud, a retaining head on said stud, and spring means on said stud for urging said mandrel or sleeve into abutment with said head.

4. A tube drawing mandrel construction comprising a mandrel shank, a stud threadedly engaging said shank, a sizing mandrel or sleeve removably carried on said stud, said mandrel or sleeve having a substantially larger internal diameter than the external diameter of said stud, and said mandrel or sleeve being shorter than said stud, whereby said mandrel or sleeve may be displaced longitudinally and a substantial amount laterally on said stud, a retaining head on said stud, spring means on said stud for urging said mandrel or sleeve into abutment with said head, and said head having a portion shaped for engagement with a tightening tool.

5. A tube drawing mandrel construction comprising a mandrel shank, a stud threadedly engaging said shank, a sizing mandrel or sleeve removably carried on said stud, said mandrel or sleeve having a substantially larger internal diameter than the external diameter of said stud, and said mandrel or sleeve being shorter than said stud, whereby said mandrel or sleeve may be displaced longitudinally and a material amount laterally on said stud, a retaining head on said stud, spring means on said stud for urging said mandrel or sleeve into abutment with said head, and said head having a portion shaped for engagement with a tightening tool and means for attaching said shank in a tube drawing apparatus.

6. A tube drawing mandrel construction comprising a mandrel shank, a stud threadedly engaging said shank, a sizing mandrel or sleeve removably carried on said stud, said mandrel or sleeve having a larger internal diameter than the external diameter of said stud, and said mandrel or sleeve being shorter than said stud, whereby said mandrel or sleeve may be displaced longitudinally and laterally on said stud, a retaining head on said stud, spring means on said stud for urging said mandrel or sleeve into abutment with said head, and said head having a portion shaped for engagement with a tightening tool and said shank having a threaded portion for attachment of said shank in a tube drawing apparatus.

7. A tube drawing mandrel construction comprising a mandrel shank having a threaded axially extending bore, a stud threadedly engaging in said bore and extending outwardly thereof, a headed portion on said stud adjacent its outermost end, a sizing mandrel or sleeve removably carried on said stud, said mandrel or sleeve having a larger internal diameter than the external diameter of said stud and said sleeve being shorter in length than said stud, whereby said mandrel or sleeve may be displaced longitudinally and laterally on said stud, and spring means on said stud for urging said mandrel or sleeve into abut-

ment with said head, said shank and said stud being of heat treated tool steel and said mandrel or sleeve being of cemented tungsten carbide.

8. A tube drawing mandrel construction comprising a mandrel shank of heat-treated tool steel, a retaining stud of heat-treated tool steel extending from said shank, and a sizing mandrel or sleeve of cemented tungsten carbide carried on said stud and being displaceable longitudinally and a material amount laterally with respect to the axis thereof.

9. A tube drawing mandrel construction comprising a mandrel shank, a stud threadedly engaging said shank, a sizing mandrel or sleeve removably carried on said stud, said mandrel or sleeve being tapered externally and having a larger internal diameter than the external diameter of said stud, and said mandrel or sleeve being shorter than said stud, whereby said mandrel or sleeve may be displaced longitudinally and laterally on said stud, a retaining head on said stud, spring means on said stud for urging said mandrel or sleeve into abutment with said head, and said head having a portion shaped for engagement with a tightening tool, and said shank having a threaded portion for attachment of said shank in a tube drawing apparatus.

10. A tube drawing mandrel construction comprising a mandrel shank, a stud threadedly engaging said shank, a sizing mandrel or sleeve removably carried on said stud, said mandrel or sleeve having a rounded edge adjacent its outer periphery at one end and a tapered edge adjacent its outer periphery at its other end, said mandrel having a larger internal diameter than the external diameter of said stud, and said mandrel or sleeve being shorter than said stud, whereby said mandrel or sleeve may be displaced longitudinally and laterally on said stud, a retaining head on said stud, spring means on said stud for urging said mandrel or sleeve into abutment with said head, said shank and said stud being of tool steel, and said mandrel or sleeve being of cemented tungsten carbide.

11. A tube drawing mandrel construction comprising a mandrel shank, a stud carried by said shank, a sizing mandrel or sleeve removably carried on said stud and being displaceable longitudinally and a material amount laterally with respect to the axis thereof, and means interposed between the said shank and said mandrel or sleeve and serving as a shock absorber to prevent shock damage to said mandrel or sleeve.
